UNITED STATES PATENT OFFICE.

MERTON DOUGLAS DAVIS, OF LONDON, ENGLAND.

FOUNTAIN PEN.

Application filed December 6, 1920. Serial No. 428,761.

To all whom it may concern:

Be it known that I, MERTON DOUGLAS DAVIS, a subject of the King of Great Britain and Ireland, residing at London, England, have invented certain new and useful Improvements in Fountain Pens; and I do hereby declare the following to be a full, clear, and exact description of the invention, such as will enable others skilled in the art to which it appertains to make and use the same.

This invention relates to improvements in fountain pens and the like devices, and has for its object an improved construction of pen of the type in which a cap is employed for closing or covering the nib or stylus end of the pen when the same is not in use, although it may be applied to other types of fountain pens.

Hitherto it has been customary to employ a filling device comprising a tubular member provided at one end with a bulb of rubber or the like by the successive compression and extension of which the air in the tube is expelled and ink drawn therein, said device being used to fill the pen reservoir when the closing plug or screwed sleeve carrying the nib and feed, has been removed.

With pens requiring a filling device of this type it is very often difficult to fill the pen when required owing to the filling device not being available.

The present invention has for its principal object an improved construction of pen and of the cap ordinarily used for protecting the nib or stylus which is shaped in such a manner as to serve as a receptacle for a filling appliance, the construction of which constitutes a novel feature of the invention.

A further feature of the invention consists in the application of the improved cap to a pen of the type in which the nib holder is telescopically mounted within the pen barrel, said holder being retracted within the barrel by rotation. With this type of pen it is usual to close the end of the barrel by a plug which may be screwed therein. In applying the invention to pens of this type, the plug or cap for closing the end of the pen barrel is extended to form a chamber for enclosing the filling device.

According to one form of the invention the outer end of the protecting cap, is formed as a chamber for the reception of the filling appliance, the latter being formed in one or more parts, preferably three, one

of which comprises a bulb of rubber or other suitable material, while the other two members comprise tubes or the like slidably one within the other, the outer tube being 60

slidable within the neck of the bulb portion. The end of the chamber for the filling appliance is closed by a separate plug or cap or the outer closed end of the bulb may be formed with a flange or shoulder, and 65 of greater thickness, which portion may or may not be vulcanized, the end of the bulb forming a close fit within the open end of the cap.

The container for the filling appliance 70 may also be provided with a springy clip adapted to frictionally hold the end of the inner member of the filling appliance, so that when the same is withdrawn from the container, the inner member is retained 75 within the container, so that the action of withdrawing the filling device also causes the same to be extended to its maximum length ready for use.

In order to fill the pen reservoir it is 80 merely necessary to remove the filling appliance from the cap, the removal of the appliance automatically extending the parts thereof to their maximum length (where a telescopic filling device is employed) the 85 appliance being used in the usual well known manner and afterwards returned to the container or chamber within the cap.

In order that the invention may be readily understood reference is made to the accompanying drawings in which:—

Fig. 1 is a sectional elevation through the nib or stylus end of the pen, with the cap in position thereon, together with the filling appliance for the ink reservoir.

Fig. 2 is an elevation of the portion of the pen shown in Fig. 1.

Fig. 3 is a sectional view of one form of cap and a view in elevation of the closing cap or plug therefor.

Fig. 4 is a sectional view of the filling appliance for use with the cap shown in Fig. 1 and showing the same in its extended position.

Fig. 5 is a similar view to Fig. 4 showing the filling device collapsed.

Fig. 6 is a modified construction in section, in which the outer end of the bulb of the filling appliance is shaped to constitute the closing plug for the chamber in 110 the cap in which the filling appliance is enclosed.

Fig. 7 is a sectional view of a modified construction of cap intended for use with pens of the type in which nib and feed are secured in a sleeve screwed into the end 5 of the pen barrel.

Fig. 8 is a detail hereinafter referred to.

In the construction illustrated in Figs. 1 and 2, the cap *a* is intended for use with pens of the type in which the holder is 10 retractible within the body of the pen barrel.

Fig. 1 shows the nib holder *b* in its retracted position within the body of the pen barrel *c*. The cap which is preferably cylindrical, is open at opposite ends to constitute two chambers *d*, *e*, respectively. The bottom of the chamber *d* is closed by a plug portion *f* as shown in Figs. 1 and 3 serving to close the open end *c*¹ of the barrel *c*, so 20 that when the nib holder *b* is retracted within the barrel (Fig. 1) the end of the barrel will be effectively closed, so that leakage of ink from the barrel is prevented. The bottom of the chamber *e* terminates in a conical 25 recess *g* for a purpose hereinafter described.

The open end of the chamber *d* of the cap is preferably threaded at *d*¹ to engage the externally threaded portion *c*² of the barrel *c* of the pen, while when the pen is removed 30 to that end of the pen body opposite to the nib holder the chamfered portion *d*² of the cap serves to enable the cap to snugly fit the pen body in the usual manner, the threaded portion *d*¹ being located a short distance 35 within the chamber *d* for this purpose.

The open end of the chamber *e* of the cap *a* is provided with a closing plug *h*, the outer periphery of which is knurled, milled or otherwise roughened, as shown to facilitate 40 its removal. The closing plug is also preferably dished or hollowed out, as shown at *h*².

The filling appliance for the pen reservoir, shown separately at Figs. 4 and 5 comprises two tubular members *k*, *l*, the part *l* being slidable within the part *k* and preferably flared out or provided with a lip or projecting flange *l*¹ engaging an inwardly turned lip on the end of the member *k* to 50 prevent the same being entirely withdrawn from the part *k*. On the part *k* is mounted a bulb *m* of rubber or other suitable resilient material within which the central tube *k* is slidably mounted, the part *k* being flared out 55 at its inner end as shown at *k*¹ while the open end of the bulb is preferably secured, as by a ring or strap of wire *n* to the inner sleeve *m*¹, the latter being preferably provided with an annular groove in its outer 60 periphery into which the material of the bulb is pressed by the band *n*, so that no wear takes place when the parts are slidden one within the other. The inner surface *k*² at one end of the member *k* is preferably 65 slightly tapered to ensure rigidity while the

outer surface of the member *k* at the opposite end is also tapered as shown for a similar purpose.

When the filling appliance is in use the members *k*, *l*, *m* are extended to their maximum length, as shown in Fig. 4, the flared ends of the members *k*, *l*, constituting a close and substantially air tight fit within the members *k*, *m* respectively, enabling the filling device to be used in the usual manner to 70 fill the ink reservoir. If desired the flared ends of the tubular members may be formed or provided with washers or packing of cotton or the like to ensure a close fit and also to remove any ink from the inner surface of 75 the tube *k* when the parts are collapsed after being used.

The conical recess *g* is preferably provided with an annular groove or undercut *g*¹ serving to receive a springy clip *s* (shown 80 in plan in Fig. 8). The clip is shaped to snugly fit the groove *g*¹ and is provided with a pair of springy arms *s*¹ between which the grooved outer end *l*² of the inner tubular member of the filling appliance engages, so 85 that when the latter is withdrawn from the chamber *e*, the inner member is retained and released only when the parts have been extended to their maximum length. By this means the withdrawal of the filling appliance 90 from the cap automatically extends the parts ready for use.

When the device is to be placed in the chamber *e* of the cap *a*, the device is held by the bulb and the end of the tube *l* is placed 100 in the chamber *e* until it rests at the bottom of the conical recess *g*. The bulb is now pushed into the chamber, the pressure exerted being sufficient to cause the three members *k*, *l*, *m* to collapse, as shown in 105 Figs. 1 and 5. The closing plug *h* is now placed in position to close the end of the chamber *e* (Fig. 1) the dished recess *h*² taking over the rounded end of the bulb *m* as shown.

As previously described the base *f* of the chamber *d* of the cap serves as a closing plug or the like for the open end of the pen barrel when the nib holder *b* has been retracted, the screw threads *c*² and *d*¹ on the barrel and 115 within the chamber *d* respectively being so arranged relatively, that when the cap *a* is screwed on to the end of the barrel *c*, the plug is drawn down on to the seating formed at the open end *c*² of the barrel immediately 120 above the nib when in its retracted position (see Fig. 1).

In the construction shown at Fig 6 the closed end of the bulb *m* is formed with an annular flange or lip *m*¹ which together with the end of the bulb is somewhat increased in thickness, as shown, so that when the filler is placed within the chamber *e* in the cap *a* the end thereof will be closed by the thickened portion or head of the bulb, the 125 130

outer surface of the latter beneath the flange m^1 forming a close fit within the open end of the chamber e .

Referring now to the construction illustrated at Fig 7, it will be seen that the body of the barrel c of the pen has screwed therein a sleeve b^1 constituting the nib and feed holder which is adapted to be removed in the usual manner when the pen is to be filled. In this construction the outer periphery of the barrel is threaded at c^2 at the point below the screwed sleeve b^1 so that when the cap a is screwed thereon there will be no tendency for the sleeve to become displaced, the cap a engaging the barrel. In this construction the cap a is provided with a wall or partition f^1 the upper side of which forming the bottom of chamber e is formed with a conical or other shaped recess g similar to the construction shown at Fig. 1. Either or both of the chambers d and e in the cap may be provided with one or more vent holes o .

It will be understood that the details of construction and arrangement of parts may be modified without departing from the principle of the invention. For instance, the cap may if desired, be made in one or more parts screwed or otherwise connected together to facilitate or reduce the cost of manufacture.

What I claim and desire to secure by Letters Patent of the United States of America is:—

35 1. A fountain pen or the like device comprising a body member, a removable protective cap member adapted to be fitted on to either end of said body, a chamber in one of said members and a removable and telescopically collapsible filling appliance housed in said chamber, said appliance comprising at

least two tubular members one of which is collapsible.

2. A fountain pen or the like device comprising a body having an ink reservoir, a nib and feed holder connected to one end of said body, a cap adapted to be attached to either end of the pen body, a chamber in the outer end of said cap, a removable filling appliance housed in said chamber, said filling appliance comprising at least two tubular members 45 slidably telescopic one within the other, one of said members being collapsible.

3. A fountain pen or the like device as 55 claimed in claim 1, wherein the protective cap for the nib or stylus is formed with two chambers separated by a partition one of said chambers forming a container for a removable filling appliance, while the other 60 chamber is adapted to fit over either end of the pen body, the partition constituting a closing plug for the pen barrel.

4. A fountain pen or the like device, as 65 claimed in claim 3 wherein the partition separating the chambers in the cap is formed on one side as a plug for the open end of the pen barrel and is provided on the opposite side with a recess to receive the end of the filling appliance.

5. A fountain pen or the like device as 70 claimed in claim 4 wherein the recess in the container for the end of the filling appliance is provided with a springy clip or the like to frictionally engage the end of the inner member thereof for the purposes set forth.

6. A fountain pen or the like device, as 75 claimed in claim 1 wherein one member of the filling appliance is shaped to constitute a closing plug or cap for the chamber in 80 which the appliance is contained.

MERTON DOUGLAS DAVIS.
